UNITED STATES PATENT OFFICE.

MARTIN J. PETERSEN, OF CANYON, MINNESOTA.

CLEANING ROD FOR GUNS.

Application filed August 12, 1927. Serial No. 212,593.

This invention relates to improvements in cleaning rods for firearms.

One object of the invention among others is to provide a device which will allow the 5 cleaning rod to rotate freely in a rifled barrel as the rod is pulled endwise through the barrel.

Another object of the invention is to provide a device which will obviate the necessity of turning the hand when the rod is drawn through a rifled barrel.

And a still further object of the invention is to provide a device which will facilitate the thoroughness of the cleaning operation.

Other objects will appear as the description of the invention proceeds.

In the drawings:

Figure 1 is a side elevation of the cleaning rod.

Figure 2 is an enlarged sectional view particularly showing the handle.

Figure 3 is a transverse sectional view on the line 3—3 of Figure 2, looking in the direction indicated by the arrows, and

Figure 4 is a view similar to Figure 2, showing a slight modification of the invention.

Referring more particularly to the drawings, the numeral 10 indicates a rod element 30 which is flattened at one end and provided with a slot 11 to receive the usual cleaning rag. Formed on the other end of said element is a disc or head 12.

35 Swiveled on the rod element 10 is a casing 13 open at one end and closed at the other end by an end wall 14 having an axial opening therein which rotatably receives said rod element. The disc 12 is freely accommodated within the casing and interposed between the end wall 14 and the disc are ball bearings 15. Overlying the disc are similar bearings indicated by the numeral 16.

45 Snugly fitting in the casing is a metal thimble 17 and associated with said thimble is a rounded grip 18 formed of wood or other suitable material. At one end said grip is reduced to form a shank 19 fitting snugly in the thimble, and formed at the 50 base of said shank is a flat shoulder 23 which overhangs the open end of the casing abutting the edge thereof. Formed in the casing

13, the thimble 17, and the reduced shank of the grip and fitting through said openings is a transverse pin 20 which is upset at both 55 ends to maintain the coacting parts in operative relation.

In use, a cleaning rag is inserted into the slot 12 and the rod element 10 is then inserted in the barrel of the gun to be cleaned. 60 As said element is drawn from the gun, the handle is held against rotation, but the rag carried by the rod element will follow the rifles, causing said element to rotate, thus aiding the cleaning of said rifles. The head 65 of the rod element will rotate freely in the casing due to the ball bearings underlying and overlying the disc. Oil should be introduced into the casing to keep the bearings in good condition.

70 Referring to Figure 4, I show a device similar to the one shown in Figures 1 and 2 with the exception that I employ a hollow rounded metal grip 22 with one end reduced to form a shank 24 which is fitted snugly within the casing 13, thus obviating the necessity for the thimble 17. Otherwise, the modification is identical with the preferred form of the invention and operates in a like manner.

80 Having thus described the invention, I claim:

A gun cleaner comprising a rod, a flat circular disk at one end of said rod constituting a head for the rod, a cylindrical casing open at one end and having a wall at its other end formed with a central opening, said rod being passed through said opening with its head received in the casing and being freely rotatable relative to the casing, bearing balls about said rod between the head thereof and the end wall of said casing, a hand grip having at one end a reduced integral portion forming a neck, the said neck being received in said casing through the open end thereof and having a flat end face spaced from the head of said rod, bearing balls in said casing between the head of said rod and the flat end face of said neck, and a securing pin passed transversely through the casing and 90 neck to firmly hold the casing in engagement with the hand grip.

95 In testimony whereof I affix my signature.
MARTIN J. PETERSEN. [L. S.]
